CHAIR

James E. Jones and Edward P. Stevens, Toledo, Ohio, assignors to The Hettrick Manufacturing Company, Toledo, Ohio, a corporation of Ohio

Application December 27, 1955, Serial No. 39,485

Term of patent 14 years

(Cl. D15—1)

FIG. 1.

The broken lines denote a section of indeterminate length.

We claim:

The ornamental design for a chair, as shown and described.
